UNITED STATES PATENT OFFICE.

BENJAMIN E. GETZ, OF MORTON, ILLINOIS, ASSIGNOR TO GETZ POWER WASHER CO.,
OF MORTON, ILLINOIS, A CORPORATION OF ILLINOIS.

WASHING MACHINE.

Application filed November 26, 1924, Serial No. 752,315.

This invention has reference to washing machines, and particularly to that type including a clothes container or tub which is mounted for movement in the frame of the machine. In its preferred form the container or tub is oscillated, but to those skilled in this art it will be understood that the movement of the operating means could be extended so as to impart an alternating 10 rotary movement to the container or tub, so as to rotate it approximately a full revolution before reversing its operation, instead of a partial rotation, as herein shown.

The object of the invention generally stated is to provide a controllable means for the tub moving means; such controllable means movable to different positions and adapted in one of its positions to impart movement to the tub and in another of its 20 positions adapted to restore the tub to normal stopped position, without stopping the movement of the tub moving means.

The invention has for a further object to operate the tub moving means from the 25 wringer operating shaft.

A further object of the invention is to connect the tub moving means direct to the wringer operating shaft and to provide a direct drive from the motor to the wringer 30 operating shaft.

The invention herein described and shown is an improvement on the generic idea disclosed in the patent to Litwiller et al. No. 1,460,203 dated June 26, 1923, and as to such 35 generic disclosure a disclaimer is here made. Reference is also made to the disclosure forming the subject matter of my copending application bearing Serial No. 631,965.

The present improvement resides in the 40 controllable means and in the operative connections between said controllable means and the wringer operating shaft. With such a structure two separate and distinct driving means between the motor and the tub 45 and between the motor and the wringer are obviated; making it possible to provide a direct drive from the motor to the wringer operating shaft and drive the tub moving means off of the wringer operating shaft. 50 Thus not only simplifying the operating mechanism but also reducing the first cost of the machine.

That the invention may be more fully understood, reference is had to the accompanying drawings, forming part of the de-

scription, and illustrating a preferred embodiment of the invention, in which:—

Figure 1 is a side elevation of a standard type washing machine with my invention embodied therein, the tub partly broken 60 away and the usual wringer mechanism omitted but showing the wringer standard, and the controllable means being in tub operating position.

Figure 2 is a detail of the tub operating 65 means and controllable means included therein, the parts having assumed a position with the wringer operating shaft having turned half way around;

Figure 3 is a view somewhat similar to 70 Figure 2, except that the controllable means has been actuated to set the tub in normal stopped position, without stopping the movement of the tub moving means;

Figure 4 is a plan view of what is shown 75 in Figure 3, the parts being in similar positions;

Figure 5 is a detail vertical sectional view 80 as the same would appear if taken on the line 5—5 Figure 3, and

Figure 6 is a detail section, in plan, as the 85 same would appear if taken on the line 6—6 Figure 3.

Like characters of reference denote corresponding parts throughout the figures. 85

I have elected to show the invention associated with a standard type washing machine embodying an oscillating tub and an upright wringer operating shaft with which a clothes wringer of standard construction 90 may have a swinging relation, like in most power operated washing machines in use today.

The frame of the machine is not unlike 95 frames used in washing machines of standard construction, except as to minor details and includes a base 1, uprights or standards 2 provided with casters 3, a top frame 4 and suitable bracing members 5, 6 and 7. The machine may be enclosed in a cabinet 100 or casing, not shown, if it is desired. The container or tub is designated 8, being preferably provided with a bracing frame 9 formed or provided with trunnions 10 journaled in bearings 11 secured to the bracing 105 member 7 of the frame. The trunnion supports for the container or tub 8 permit it to be oscillated within or on the frame, and said tub has an opening 12 through which clothing or other material would be inserted 110.

into and withdrawn therefrom, and such opening covered or closed, when desired, by a suitable lid or cover, not shown.

On the base 1 of the machine is supported an electric motor 13. Also on the base 1 is a mounting 14 in which is journaled and from which upstands a wringer operating shaft 15 having bearing supports in the top frame 4 and a bracing member 6. Said operating shaft 15 preferably derives its power direct from the motor 13 through a shaft 16 coupled to the motor through a flexible coupling 17 and having operative connection with the wringer operating shaft 15 through worm wheel gearing 18. To the upper end of said wringer operating shaft is suitably connected a wringer standard 19 arranged to have rotative connection with said shaft whereby said standard may be swung about said shaft, into different positions. Said standard serves as a support for a clothes wringer, not shown, but which would be power operated from the shaft 15. The wringer may include the usual and customary clutch control for operatively connecting and disconnecting the wringer with the shaft 15, at the will of the attendant or operator, as will be understood.

In Figure 3, the container or tub has been restored to its normal position, or as some would say returned to its neutral position, and stopped, the tub moving means continuing in operation, and the controllable means idling and without movement being imparted to the container or tub. In Figures 1 and 2 the controllable means has been moved to a position which will cause the tub moving means to impart movement through the controllable means to the tub, and as a result the tub is oscillated back and forth, Figures 1 and 2 showing the parts in two different positions.

By "normal" or "neutral" position of the tub, it is to be understood that that is the position the tub occupies when it is stopped, as in Figure 3, so that the lid or cover thereof may be removed by an attendant to permit the removal of clothes or fabrics from the tub and the placing of other articles or materials therein. Also, by the use of the word "restore" I mean bringing back or righting of the tub to "normal" or "neutral" position at the same time that the operating means is made ineffective so far as operating the tub is concerned, yet without disturbing the movement of the tub moving means.

The tub moving or operating means comprises a crank 20 formed in or connected to the wringer operating shaft 15 and adapted to be continuously rotated with said shaft as the latter is rotated through the driving connections described with the motor 13.

To the crank 20 is pivotally connected a coupling 21 to which is pivotally connected

one end of a pitman arm or bar 22, the opposite end of which has a pivotal connection with a controllable means, to be described, in operative connection with the clothes container or tub 8.

To the projecting end of one of the trunnions 10 of the tub 8 is secured a crank arm 23 and to said crank arm is connected a strap 24 which engages a slidable rod or bar 25. To one end of said bar or rod, being the upper end, is secured an off-set bracket 26 to which is pivotally connected the inner end of a hand operated lever 27 fulcrumed to the brace member 5. To the opposite, or lower end of said bar or rod 25 is secured a collar 28 and on the rod or bar between said collar and strap 24 is a strap 29 to which the pitman bar or rod 22 has a pivotal connection. I prefer to fix the position of the strap 29 on the rod or bar 25 and therefore groove said bar or rod, as at 30 and provide the strap 29 with a screw 31 adapted to enter said groove.

When the tub moving means and the controllable means included therein have been assembled and coupled to the trunnion 10 of the tub and the operator's lever 27 the point of pivotal connection between the lever and the off-set bracket 26 may be moved in an arc, due to the fulcrum of the lever 27, to intersect the axis of the trunnion 10, as in Figures 1 and 2 and intersect the axis of the crank arm 23 forming the pivotal point of connection with the strap 24 which engages with the bar or rod 25, as in Figure 3. In the latter position, as the shaft 15 is revolved and the crank arm 20 is rotated reciprocating the pitman bar or rod 22 in a substantially horizontal plane, the rod or bar 25 is oscillated to and fro or forward and backward on the pivot between the strap 24 and the crank-arm 23 which in this instance is in coincidence with the pivot between the inner end of the lever 27 and the off-set bracket 26, being the neutral position of the controllable means, and in which position of the parts the container or tub is in normal position and stopped, or in other words no movement will be imparted to said container or tub, although the operating means comprising the shaft 15 and connections to the strap 29 may continue to operate, as it is believed will be understood. In this position, also, the rod or bar 25 may be said to be in its lowermost position, as shown, with the outer end of the operator's lever 27 raised.

When the outer end of the lever 27 is lowered the inner end lifts the rod or bar 25 into its uppermost position, see Figures 1 and 2 bringing the pivot between the inner end of the lever and the off-set bracket 26 into coincidence with the axis of the trunnion 10, in which position of the parts, and as the rod or bar 25 is oscillated, it will im-

part oscillatory movement to the crank arm 23 and in turn impart a like movement to the container or tub. As shown in Figure 3 the fulcrum of the lever 27 is located at a point to one side of a vertical line intersecting the axes of the pivot between the lever and the off-set bracket and in a horizontal plane which intersects such vertical line midway between the axes of the trunnion 10 and the coinciding pivots of the crank-arm 23, strap 24 and the inner end of the lever 27. Thus, when the pivot of the inner end of the lever 27 and the off-set bracket is in coincidence with the pivot of the strap 15 with the crank-arm 23 the container or tub is not only in a neutral position but is held locked in such position during the rotation of the shaft 15 and the reciprocation of the bar or rod 22. Likewise, when the lever 27 has been moved to place the controllable means into operative position with the pivot of the lever with the off-set bracket in coincidence with the axis of the trunnion 10 the parts will be held in operative position, whereby oscillatory movement may be imparted through the rod or bar 25 and the crank arm 23 to the container or tub. The latter is restored to neutral position and stopped when the lever 27 and controllable means are moved from a position similar to that shown in either Figure 1 or Figure 2 to a position similar to that shown in Figure 3. From the foregoing it will be observed that by the gradual movement of the lever 27 from the position shown in Figure 3 to the position shown in Figures 1 or 2 that the tub oscillation would be slow with a short stroke gradually increasing until the full stroke is reached. The reverse of this is also true when the lever is moved from the position shown in Figures 1 or 2 to the position shown in Figure 3. When the oscillation may be gradually slowed down until

the tub is brought to a stop. Holding the lever at points intermediate its full throw 45 will permit a varying stroke to be imparted to the tub.

What I claim is:—

1. In a washing machine, in combination, a tub mounted for oscillation, a crank arm 50 in axial connection with said tub, a slidably arranged rod, connections between said rod and said crank arm, a lever for sliding said rod to move it alternately into operative and inoperative positions, and during such movement to the latter position bringing the tub to its normal position, a power means, a vertically disposed shaft arranged to operate a wringer and to impart oscillatory movement to said rod, a crank in connection 55 with said shaft to rotate therewith, and reciprocal connections between said crank and said rod.

2. In a washing machine, in combination, a tub mounted for oscillation, a crank arm 60 in axial connection with said tub, a slidably arranged rod, a pivotal connection between said rod and said crank arm, a lever, a pivotal connection between said lever and said rod arranged to be alternately brought into 65 axial coincidence with the axis of the tub and the pivotal connection between said rod and said crank arm and during such movement to the latter position bringing the tub to its normal position, a power means, a 70 vertically disposed shaft driven by said power means arranged to operate a wringer and to impart oscillatory movement to said rod, a crank in connection with said shaft to rotate therewith, and reciprocal connections between said crank and said rod. 75

In witness whereof, I have hereunto affixed my hand this 22nd day of November, 1924.

BENJAMIN E. GETZ.
